CLAIM

We claim the ornamental design for a light fixture housing, as shown and described.

DESCRIPTION

FIG. 1 is a front perspective view of a light fixture housing embodying the present invention.

FIG. 2 is a front view of the design shown in FIG. 1.

FIG. 3 is a rear view of the design shown in FIG. 1.

FIG. 4 is a left side view of the design shown in FIG. 1.

FIG. 5 is a right side view of the design shown in FIG. 1.

FIG. 6 is a top view of the design shown in FIG. 1; and,

FIG. 7 is a bottom view of the design shown in FIG. 1.

The portions of the light fixture housing shown in broken lines form no part of the claimed design.
